UNITED STATES PATENT OFFICE.

ARVY W. WAGNER, OF GRAFTON, WEST VIRGINIA.

WASHBOARD-HOLDING MEANS.

Application filed December 4, 1923. Serial No. 678,465.

To all whom it may concern:

Be it known that I, ARVY W. WAGNER, citizen of the United States, residing at Grafton, in the county of Taylor and State 5 of West Virginia, have invented certain new and useful Improvements in Washboard-Holding Means, of which the following is a specification.

This invention relates to washboards and 10 has particular reference to means for holding a wash board in its proper inclined position within a wash tub.

The primary object of the invention is to 15 provide a wash board holding means of the above kind, which embraces the desired qualities of simplicity and durability of construction, as well as efficiency in operation.

Another object of the invention is to provide a wash board holding means of the 20 above character, which may be cheaply and easily manufactured and placed into use, in an easy and expeditious manner, without the requirement of special tools or skill.

Still another object of the invention is 25 to provide a washboard holding means which may be readily applied to or removed from a washboard, so that when one washboard becomes worn out, the holding means may be removed and applied to a new one.

Still another object of the invention is to 30 provide a wash board holding means comprising clamps which may be adjusted to engage wash boards of different kinds and contour for effective operation.

Other objects will appear as the nature 35 of the invention is better understood, and the same consists in the novel form, combination, and arrangement of parts hereinafter more fully described, shown in the accompanying drawings, and claimed.

In the drawing, wherein like reference characters indicate corresponding parts throughout the several views:

Figure 1 is a top plan view showing a 40 wash board operatively disposed within a wash tub and held in proper position by means of holding means constructed in accordance with the present invention.

Figure 2 is an enlarged fragmentary side 45 elevational view of the washboard shown in Figure 1, and illustrating details of construction of the clamp members, and

Figure 3 is an enlarged plan view of the blank from which the plates of the clamp 50 members are formed.

Referring more in detail to the drawing,

the present invention consists in the provision of right and left hand clamp members of similar general construction that are secured to opposite sides of the wash board 60 5 adjacent the upper end of the latter in position to engage the wall of a wash tub 6 for supporting and holding said wash board in its proper inclined position.

As these clamps are of similar construction with the exception that one of the same is formed to be secured upon the left hand side of the wash board, and the other for being secured to the right hand side of said wash board, description of one of the same 70 will suffice. As shown clearly in Figures 1 and 2, each clamp comprises a plate 7, the lower end of which is slotted or bifurcated to provide a pair of legs 8 and 9 between which the upper edge of the wash tub wall is adapted to be disposed, the inner leg 8 forming the inner jaw of the clamp member as will presently become apparent. Rigid or integral with the inner edge portion of the leg 9 is a laterally extending ear 10, 75 80 that is preferably formed by stamping the same from the plate 7 to form the slot or spaced between the legs 8 and 9, and the opening of this ear 10 is screw threaded for threaded reception of the stem of a clamping screw 11, upon the inner end of which is a head or jaw member 12 adapted to engage the outer surface of the wash board wall and to tightly draw the inner edge of the leg jaw 8, into engagement with the inner 85 90 surface of said wash board wall, for rigidly securing the washboard in place. The sheet metal from which the plate 7 is formed is preferably flexible, so that the ear 10 may be flexed at any desired angle relative to 95 the plane of the plate 7, for proper engagement of the jaw 12 with the tub. When used in connection with circular tubs as shown in Figure 1, the ear 10 will extend obliquely to the transverse axis of the plate 7, so as 100 to properly engage the wall of said tub, while with stationary wash tubs of rectangular form, the ear 10 will extend substantially perpendicular to the plate 7. The ear 10 may be flexed manually to adapt the 105 clamp member to the particular form of tub, in which the wash board is to be held or supported, and for facilitating rotation of the clamping screw 11, a knurled head or knob 13 may be provided upon the outer end 110 of the latter.

The manner in which the ear 10 is struck

from the body of the plate 7, is shown clearly in Figure 3, and the dotted lines 14 indicate the point at which the ear is bent relative to said plate.

5 The upper edge of the plate 7 is preferably inclined as at 15 in accordance with the inclination which the wash board will assume when properly positioned in the tub, and this plate is provided at its upper corner 10 with openings 16 through which screws 17 may be passed for being threaded into the side bars of the board 5 to secure the clamp members rigidly to the latter.

In operation, the wash board, which has 15 been previously equipped with right and left hand clamp members constructed in accordance with the above and as shown in Figure 1, is placed within the tub, so that the wall of the latter passes between the legs 20 8 and 9 of both clamp members, whereby the screw 11 is adjusted inwardly to engage the jaws 10 tightly with the outer surfaces of the top wall, and to draw the inner edges of the jaw legs 8, into tight engagement with 25 the inner surface of said top wall. When this is done, the wash board is rigidly and

effectively held in its proper inclined position, so that the person engaged in washing clothes upon the board 5 may have both hands free for facilitating the washing operation. The clamp members will also hold the lower end of the board spaced from the wall of the tub so as to leave considerable room for the clothes within the tub and for allowing free reciprocation of the clothes 30 35 upon the surface of the wash board.

The device is effective and simple in construction, as well as easily applied and removed and may be supplied to the public at a small and nominal cost.

40 What I claim as new is:

Wash board holding means comprising a substantially flat plate adapted to be attached to one of the side plates of the wash board, said plate having an ear struck out 45 from its lower edge and bent to extend at right angles thereto, said ear being equipped with a screw threaded opening, and a clamping screw threaded through said opening.

45 In testimony whereof I affix my signature.

ARVY W. WAGNER.
